UNITED STATES PATENT OFFICE.

GEORGE D. POGUE, OF ST. LOUIS, MISSOURI.

WATER-COOLED PISTON.

1,181,326.

Specification of Letters Patent.

Patented May 2, 1916.

Application filed April 17, 1915. Serial No. 21,987.

To all whom it may concern:

Be it known that I, GEORGE D. POGUE, a citizen of the United States, residing at St. Louis, Missouri, have invented a certain new and useful Improvement in Water-Cooled Pistons, of which the following is a full, clear, and exact description, such as will enable others skilled in the art to which it appertains to make and use the same.

10 This invention relates to water-cooled pistons of the type that are equipped with two extensible water conduits for conducting the cooling water to and from the water chamber in the piston, each of said conduits consisting of a depending tube on the piston that is arranged in telescopic relation with a stationary tube.

In water-cooled pistons of the general type mentioned great skill and care has to be exercised in positioning the coöperating stationary and movable water tubes so that they will telescope freely without binding or causing the tubes to become bent or the connections between same and the parts on 25 which they are mounted strained when the piston is in operation, owing to the fact that the movable tubes are rigidly connected to the piston and the stationary tubes are rigidly connected to a supporting structure 30 which remains at rest when the piston is in operation. Slight inaccuracies in machining frequently result in damage or breakage of the water tubes of pistons of the type mentioned, and very often the coöperating tubes 35 are thrown out of accurate alinement by a slight rotary movement of the piston, caused by wear on the wrist pin.

The main object of my present invention is to provide a water-cooled piston of the 40 general type mentioned, in which the water conduits are so designed that they will not be damaged or broken by malalinement or slight inaccuracies in machining of the movable and stationary tubes constituting said 45 conduits.

Another object is to provide an extensible water conduit for water-cooled pistons which is so designed that one of the tubes of same can move slightly with relation to the part which carries it without causing said tube to bend or its connection with said part to be strained, in case the movable and stationary tubes of the conduit are not in absolute longitudinal alinement or concentric relation with each other. And still another object is to provide a water-cooled

piston of the general type mentioned, in which one of the water tubes is provided with two tubular-shaped portions arranged one inside of the other and connected together at one end, one of said tubular-shaped portions being connected at its opposite end to the part that carries said tube, thus leaving the other tubular-shaped portion free to move slightly with relation to the part that carries the tube.

Other objects and desirable features of my invention will be hereinafter pointed out.

Figure 1 of the drawings is a vertical sectional view of a water-cooled piston constructed in accordance with my invention. Figs. 2 and 3 are similar views, illustrating slight modifications of my invention. Fig. 4 is a detail vertical sectional view, illustrating one manner of forming the movable tube 75 of the piston shown in Fig. 1; and Fig. 5 is a detail vertical sectional view, illustrating one manner of forming the movable tube of the piston shown in Fig. 2.

I have herein illustrated my present invention embodied in a water-cooled piston of the general design illustrated and described in my pending application for water-cooled pistons, Serial #966, filed January 7, 1915, which piston is provided with a casting for receiving and collecting any water that leaks out of the joint between the coöperating stationary and movable tubes that form one of the water conduits of the piston, the stationary tube and the water-collecting 80 casing that surrounds same both being provided with stuffing boxes through which the movable tube on the piston projects. I wish 85 it to be understood, however, that my present invention is not limited to a water-cooled piston of the particular type just referred to, or, in other words, a piston of the kind described in my said pending application, for my present invention is applicable to any type of water-cooled piston equipped 90 with a water conduit formed by a movable tube and stationary tube arranged in telescopic relation to each other.

Referring to Fig. 1 of the drawings, which illustrates one form of my invention, A designates a trunk-type piston which is provided adjacent its upper end with a water space or chamber 1 through which cooling water circulates when the piston is 105 in operation. The cooling water is supplied 110 to said water space and conducted away from same by means of two extensible con-

duits, each of which is formed by a stationary tube 2 that is provided at its upper end with a stuffing box 3 through which a depending tube on the piston A passes. Each 5 of said water conduits is provided with a casing 4 that surrounds the stationary tube 2, so as to receive and collect any water that leaks through the stuffing box 3 when the packing of same becomes worn, said casing 10 4 being preferably provided at its upper end with a stuffing box 5 through which the depending tube on the piston A passes, so as to eliminate any possibility of water escaping into the crank case of the engine, the 15 packing of said stuffing box 5 operating to wipe off any water or moisture which might remain on the movable tube on the piston A on the upward stroke of the piston.

In order to overcome the objectionable results occasioned by malalignement of the 20 cooperating movable and stationary tubes of the water conduits or slight inaccuracies in the machining of said parts, I have constructed the water conduits of my improved 25 piston in such a manner that one tube of each conduit can move slightly with relation to the part that carries same without liability of straining the connection between said tube and part or subjecting either tube 30 of the conduit to side thrusts or strains which might tend to bend them. I can accomplish this desirable result in various ways, and while I prefer to mount the movable tube, or, in other words, the tube on 35 the piston, in such a manner that the portion of same which coöperates with the stationary tube can move or yield slightly with relation to the piston, I do not wish it to be understood that my broad idea is limited to 40 such a structure, for the same results can be accomplished in various ways without departing from the spirit of my invention.

In the form of my invention illustrated in Fig. 1 the movable tube of each conduit is 45 provided with two tubular-shaped portions *a* and *b* arranged one within the other and having their lower ends connected together at 7, as shown in Fig. 1. The outer portion *b* of said tube is snugly embraced by the 50 stuffing boxes 3 and 5 of the stationary tube 2 and the casing 4, respectively, and the upper end of the inner tubular-shaped portion *a* of said tube is rigidly connected in any suitable manner to the bottom wall of the 55 water space 1 in the piston A. The upper end of the outer portion *b* of the movable tube is free, and as said outer portion *b* is connected to the inner portion *a* at only one point, namely, at the lower end of same, said 60 outer portion *b* can move or flex slightly with relation to the inner portion *a* which is rigidly connected to the piston without liability of straining the joint between the portion *a* and the piston and without liability 65 of distorting or permanently bending either

tube of the conduit, in case said tubes are not in absolute longitudinal alinement or concentric relation with each other. In other words, the movable tube of the conduit consists of two tubular-shaped portions arranged one inside of the other and connected together at one end, the portion which is not engaged by the stuffing boxes 3 and 5 being secured to the piston, and thus acting as a support for the other portion, so as to hold same in position, but still permit it to bend or move sufficiently to compensate for slight inequalities in the alinement of the movable and stationary tubes. It is immaterial how the two portions *a* and *b* of the movable tube are joined together, but one convenient way of forming the movable tube is to form same from pieces of tubing whose lower ends are brazed, soldered or riveted together, as shown in Fig. 4.

If desired, the movable tube of my improved conduit can consist of an inner tubular-shaped portion *a'* that passes through the stuffing boxes 3 and 5 previously mentioned, and an outer tubular-shaped portion *b'* rigidly connected at its lower end to the piston and having its upper end joined to the upper end of the inner tubular-shaped portion *a'* at 7^a, as shown in Fig. 2, the connection between the two portions *a'* and *b'* of the tube being effected in any suitable manner, as, for example, as illustrated in Fig. 5 and preferably located far enough away from the point where the portion *b'* is connected to the piston to permit the inner portion *a'* to move or flex sufficiently to compensate for inequalities in alinement of the two tubes without danger of distorting either tube or straining the connection between the movable tube and the piston on which it is mounted.

If desired, one portion of the movable tube can be formed by a corrugated tubular-shaped member, as illustrated in Fig. 3, wherein the portion *b'* of the movable tube that is connected to the piston is provided with annular corrugations that add greatly to the flexibility of the tube.

A water-cooled piston of the construction above described is a decided improvement 115 on the water-cooled pistons of this general type which are now in general use, owing to the fact that each water conduit of same is so constructed that there is no danger of the two coöperating tubes constituting same becoming bent or strained or the connections with their supporting parts broken, in case the tubes are not in absolute longitudinal alinement and concentric relation with each other.

Having thus described my invention, what I claim, and desire to secure by Letters Patent, is:

1. A water-cooled piston provided with an extensible water conduit composed of a

- movable tube and a stationary tube arranged in telescopic relation with each other, one of said tubes having means which permits said tube to move sufficiently with relation to the part which carries same to compensate for slight inaccuracies in the alinement of the tubes and thus prevent damage to said tubes or straining of the connections between said tubes and the parts that carry same.
- 10 2. A water-cooled piston provided with an extensible water conduit composed of a stationary tube and a movable tube arranged in telescopic relation with each other, one of said tubes being provided with a portion 75 that can move or flex slightly so as to compensate for malalinement or slight imperfections in the machining of the coöperating parts of the structure.
3. A water-cooled piston provided with an extensible water conduit composed of a stationary tube and a movable tube arranged in snug engagement with each other and in telescopic relation, one of said tubes having a means that causes said tube to adjust itself 80 automatically to the position of the other tube without liability of straining or bending either tube in case the tubes are not in absolute longitudinal alinement and concentric relation with each other.
- 80 4. A water-cooled piston provided with an extensible conduit composed of a stationary tube and a movable tube, a stuffing box on one of said tubes through which the other tube projects, and means whereby one 85 tube can move or flex slightly with relation to the part which carries same without liability of straining its connection with said part in case said tubes are not in perfect alinement.
- 40 5. A water-cooled piston provided with an extensible conduit composed of a stationary tube and a movable tube arranged in telescopic relation with each other, one of said tubes being provided with a means that 90 permits said tube to shift laterally slightly so as to compensate for inequalities in longitudinal alinement of the tubes without liability of straining the connection between either tube and the part which carries same.
- 45 6. A water-cooled piston provided with an extensible water conduit composed of a stationary tube and a movable tube arranged in telescopic relation with each other, one of said tubes having a stuffing box through 95 which the other tube passes, a supporting member for one tube, and means interposed between said supporting member and tube which permits said tube to move or flex slightly to compensate for inaccuracies in 100 the alinement of the tubes.
- 55 7. A water-cooled piston provided with an extensible conduit composed of a stationary tube and a movable tube arranged in telescopic relation with each other, one of said tubes having two tubular-shaped por- 105 tions arranged one within the other and connected together at only one end, thereby permitting one of said tubular-shaped portions to move or flex slightly with relation to the other tubular-shaped portion in case the two 110 tubes are not in accurate alinement.
8. A water-cooled piston provided with an extensible conduit composed of a stationary tube and a movable tube arranged in telescopic relation with each other, one of said tubes having two tubular-shaped portions arranged one within the other and connected together at only one end, and one of said portions being connected at its opposite end to a supporting structure.
- 85 9. A water-cooled piston provided with an extensible water conduit composed of two telescoped tubes, means for forming a tight joint between said tubes, a supporting structure for one of said tubes, and a tubular-shaped member on said supporting structure to which one end of said tube is connected in such a manner that the free end of same can move with relation to said tubular-shaped member.
- 90 10. A water-cooled piston provided with an extensible water conduit consisting of a stationary tube provided with a stuffing box, a movable tube that projects through said stuffing box, and a tubular-shaped supporting device for one of said tubes arranged in concentric relation with same and connected thereto in such a manner that said tube has a certain degree of resiliency or flexibility.
- 95 11. A water-cooled piston provided with an extensible water conduit composed of a stationary tube provided with a stuffing box, a movable tube that passes through said stuffing box, and a tubular-shaped member on the piston arranged in concentric relation with said movable tube and connected to one end of same by a joint which is of such a character that said movable tube can flex or bend slightly.
- 100 12. A water-cooled piston provided with an extensible water conduit that consists of a stationary tube and a movable tube on the piston that is arranged in telescopic relation with said stationary tube, said movable tube having two tubular-shaped parts one 110 arranged inside of the other, said parts being connected together at one end and one of said parts being rigidly connected at its opposite end to the piston.
- 115 13. A water-cooled piston provided with a water space, a depending water tube on said piston that communicates with said water space, and means for permitting said tube to move or flex slightly with relation to the piston and the stationary member 120 through which said tube passes.
14. A water-cooled piston provided with an extensible water conduit that consists of a stationary tube provided with a stuffing box, a movable tube on the piston provided 130

- with two tubular-shaped portions arranged one within the other and connected together at one point, one of said tubular-shaped portions projecting through the 5 stuffing box in said stationary tube and the other tubular-shaped portion being connected to the piston, and a casing for receiving and collecting any water that escapes through the joint between said tubes.
- 10 15. A water-cooled piston provided with an extensible conduit composed of a stationary tube provided at its upper end with a stuffing box, a movable tube provided with a tubular-shaped portion that passes through 15 said stuffing box and an inner tubular-shaped portion that is rigidly connected at its upper end to the piston, the lower ends of said tubular-shaped portions being joined together.
- 20 16. A water-cooled piston provided with an extensible water conduit that consists of a stationary tube provided at its upper end with a stuffing box, a movable tube that projects through said stuffing box, and a tubu-

lar-shaped member on the piston surrounding said movable tube and connected to the upper end of same at a point some distance from the connection between said tubular-shaped member and the piston. 25

17. A water-cooled piston provided with an extensible water conduit that consists of a stationary tube provided at its upper end with a stuffing box, a movable tube that projects through said stuffing box, and a tubular-shaped member on the piston surrounding said movable tube and connected to the upper end of same at a point some distance from the connection between said tubular-shaped member and the piston, said tubular-shaped member being provided with corrugations. 30 35

In testimony whereof I hereunto affix my signature in the presence of two witnesses, this fourteenth day of April, 1915.
